UNITED STATES PATENT OFFICE

159,614

ALBUM OR SIMILAR ARTICLE

David Hersh, Los Angeles, Calif., assignor to Hollywood Innovations, Inc., Los Angeles, Calif.,
a corporation of California

Application August 7, 1948, Serial No. 147,991

Term of patent 3½ years

(Cl. D6—2)

To all whom it may concern:

Be it known that I, David Hersh, a citizen of the United States of America, residing in the city of Los Angeles, in the county of Los Angeles, State of California, have invented a new, original, and ornamental design for an Album Book or Similar Article, of which the following is a specification, reference being had to the accompanying drawing forming a part thereof.

Fig. 1 is a perspective view of an album book or similar article showing my new design;

Fig. 2 is a front elevation of the same, with a picture shown in phantom outline within the frame to indicate the method of use; and

Fig. 3 is a plan view thereof.

I claim:

The ornamental design for an album book or similar article, substantially as shown.

DAVID HERSH.
